UNITED STATES PATENT OFFICE.

HUGO A. BECKER AND ALFRED D. DUKELOW, OF ROCHESTER, NEW YORK, ASSIGNEES
TO SILL STOVE WORKS, OF ROCHESTER, NEW YORK, A CORPORATION OF NEW YORK.

COMBINED COAL AND GAS WATER-HEATER.

1,248,793

Specification of Letters Patent.

Patented Dec. 4, 1917.

Application filed November 10, 1916. Serial No. 130,523.

To all whom it may concern:

Be it known that we, HUGO A. BECKER and ALFRED D. DUKELOW, both of Rochester, in the county of Monroe and State of New York, have invented certain new and useful Improvements in Combined Coal and Gas Water-Heaters; and we do hereby declare the following to be a full, clear, and exact description of the same, reference being had 10 to the accompanying drawings, forming a part of this specification, and to the reference characters marked thereon.

Our invention has for its purpose to provide a water heating appliance in conjunction with a coal stove, with provision that permits it to be utilized also with gas heating means so that the water may be heated from gas or coal selectively, thus making it possible to quickly obtain a supply of heated 20 water when the coal side of the stove is not in operation. A more particular object of the improvement is to afford a structure of the general type above mentioned with the parts so constructed as to obtain great efficiency 25 from the gas heater, by causing a relatively small amount of water to travel over a maximum extent of heated surface, thus reducing to a minimum the time required for bringing the water up to the normally desired 30 temperature. A further object of the invention consists in providing a fairly simple and economical manufacturing and assembling structure, also to permit of making repairs with a fair degree of ease, and so 35 placing the device on an ordinarily commercial basis. To these and other ends the invention consists in certain improvements and combinations of parts all as will be hereinafter more fully described, the novel 40 features being pointed out in the claims at the end of the specification.

In the drawings:

Figure 1 is a view in side elevation of a coal stove equipped with the invention; 45 Fig. 2 is a sectional view on the line 2^a-2^a of Fig. 1;

Fig. 3 is a sectional view on the line 3^a-3^a of Fig. 2, and

Fig. 4 is a plan view of the burner employed in the gas heated chamber.

Similar reference characters throughout the several views indicate the same parts.

The invention consists generally in providing a water compartment which is pref-

erably similar to the usual water back or water front, and arranging it so as to constitute one side of the fire-box of a coal stove. Adjacent to the outer surface of the water compartment is a gas heated chamber that is separated from the fire-box by the water compartment referred to, and arranged in the gas heated chamber is a series of vertically extending water conducting coils that communicate with the upper and lower portions of the water compartment and are heated by suitable gas burning means. The water conducting coils are connected in multiple with the water compartment so that when the gas chamber is in operation, the volume of water is divided up into a number of relatively small streams that are independently heated as it passes simultaneously through the different coils, and these are arranged and heated in such a way as to insure a quick heating operation from the water traveling over a maximum heated surface.

In the embodiment illustrated and described in the present application, 1 designates the fire-box of a coal stove, having grate sections 2 and fire brick walls 3 at the front, back and along one side. The opposite side of the fire-box is formed by a hollow water compartment, the inner wall of which is designated by 4 and the outer wall 5. The water compartment is connected with the water supply or boiler through the inlet and outlet openings 6 and 7 respectively, connecting with inlet and outlet pipes 8 and 9 respectively. 10 designates a horizontal web or partition extending from one end of the water compartment to the other, separating it into upper and lower portions or chambers 11 and 12, and it is further provided at its forward end with an opening 13 permitting circulation of the water from the lower portion 12 to the upper portion 11 when heated by coal from the fire-box 1.

For the purpose of heating water when the fire-box 1 is not in use, we employ a gas heated chamber 14 adjacent to the outer wall 5 of the water compartment and formed by suitable side and bottom walls 15 and 16 respectively, while 17 designates a door that is hinged to the side of the gas heated chamber to permit ready access thereto. Arranged within the gas heated chamber are water conducting coils 18, each of which is

comparatively wide, or of large diameter, as compared with its length, for a purpose that will appear more clearly presently. A series of these coils is used, the ends of each coil 5 being connected with the upper and lower chambers respectively of the water compartment as shown in Fig. 2 clearly, where 19 designates the upper end of a coil that is connected with the upper chamber 11, and 10 20 designates the lower end connected with the lower chamber 12. In the operation of the gas heated chamber, the water circulates simultaneously through the several coils 18 from the bottom upwardly, being heated by 15 the means that will now be described.

The preferred form of burner is illustrated in Fig. 4 and incorporates a series of burners, one for each of the coils 18, and conforming substantially to the shape of the 20 end of the coil. Each burner 21 is of substantially circular formation and is disposed beneath the lower end of the corresponding coil with fuel openings which direct the flame upwardly in a circular like formation, 25 that insures heating every portion of the coil. This heating effect is due to the circular like arrangement of the burner, substantially coextensive with the end of the coil, and also to the fact that the coil is of 30 comparatively short length, so as to maintain as far as possible an even degree of heat throughout the length of the coil as the heat of the flame carries toward the top of the coil. This even distribution of heat, and 35 directing it around the entire diameter of the coil, causes the water to be subjected in relatively small streams to heated surfaces of maximum extent in a given time, and reduces to a very large degree the time required for heating a given amount of water. 40 When a coal stove is in operation, the matter of heating water is not a great problem because a certain supply of hot water is always available, but when the coal stove is 45 not in use or when it is desirable to supplement the heat from the coal, and a supply of hot water is wanted, it is very essential that it be obtained in the quickest possible time. With the present apparatus, this can 50 be accomplished in a few minutes, as compared with other types of heaters that require anywhere from ten to thirty minutes to obtain a normal supply of hot water.

In order to assist in the water heating operation, when the gas chamber is in use, we 55 also employ a burner 22 extending lengthwise of the gas heater chamber and preferably forming, in part, continuations of the circular burner sections 21. The burner 22 60 is provided with a series of fuel openings 23 which are inclined slightly toward the water compartment in order to direct the flame toward the water coils 18, and also toward the lower part or chamber 12 of the water 65 compartment. This results in heating the

water conducting coils quickly, and also heating the outer wall of the water compartment, which assists in bringing the temperature of the water up to the desired point in a minimum space of time. It will be observed 70 that access can be readily had to the gas heated compartment, and to the coils 18 independently of each other, so that any one of the coils may be removed and replaced if necessary. Inasmuch as the coils are secured only at their opposite ends, free expansion and contraction is permitted without loosening the joints where connection is made with the water compartment, and these are advantages which contribute to 75 80 ward making the device not only efficient, but practicable and commercial.

The water compartment, while herein shown and described as similar to a water front or water back, need not necessarily be 85 of this particular form, but may be of any character suitable for conducting the water from the inlet to the outlet pipes leading to the boiler, and forming in part or entirely one side of the fire-box, so that the 90 water compartment is subjected on one side to heat from the fuel in the fire-box, and on the other side to heat from the gas heated chamber. It will be understood, of course, that when we refer to the gas heated chamber throughout the specification and claims of this application, we intend to include any other fluid or liquid fuel, as distinguished 95 from wood, coal, or coke.

We claim as our invention:

1. In a combined coal and gas water heater, the combination with a water compartment forming one wall of a fire-box, of a gas heated chamber located adjacent to the fire-box, a series of water conducting 105 coils arranged vertically in the gas heated chamber and communicating at their ends with upper and lower portions of the water compartment, and gas heating means located beneath the coils.

2. In a combined coal and gas water heater, the combination with a water compartment forming one wall of a fire-box, of a gas heated chamber located adjacent to the fire-box, a series of water conducting 115 coils arranged vertically in the gas heated chamber and communicating at their ends with upper and lower portions of the water compartment, and a gas burner arranged beneath each coil and conforming substantially 120 to the end thereof whereby to expose the water to a maximum extent of heated surface.

3. In a combined coal and gas water heater, the combination with a water compartment forming one wall of a fire-box, of a gas heated chamber located adjacent to the fire-box, a series of water conducting 125 coils arranged vertically in the gas heated chamber, each coil having a comparatively 130

large diameter and short length and communicating at its ends with upper and lower portions of the water compartment, and a gas burner located beneath and conforming generally to the end of the coil whereby the water is exposed to a maximum extent of heated surface.

4. In a combined coal and gas water heater, the combination with a water compartment forming one wall of a fire-box, of a gas heated chamber located adjacent to the fire-box, a series of water conducting coils arranged vertically in the gas heated chamber and communicating at their ends with upper and lower portions of the water compartment, and gas heating means arranged in the gas heated chamber and acting to direct a flame upwardly toward the coils and also laterally toward the lower part of the water compartment.

5. In a combined coal and gas water heater, the combination with a water compartment forming one wall of a fire-box and having a centrally arranged horizontal partition with an opening at one end and inlet and outlet openings at the opposite end disposed below and above the partition respectively, of a gas heated chamber located adjacent to the fire-box, a series of water conducting coils arranged vertically in the gas heated chamber between the ends of the water compartment and communicating at their ends with upper and lower portions thereof above and below said partition, and gas heating means below the coils including

a series of burners conforming substantially to the ends of the coils.

6. In a combined coal and gas water heater, the combination with a water compartment forming one wall of a fire-box and having a centrally arranged horizontal partition with an opening at one end and inlet and outlet openings at the opposite end disposed below and above the partition, of a gas heated chamber located adjacent to the fire-box, a series of comparatively short and wide water conducting coils arranged vertically in the gas heated chamber between the ends of the water compartment and communicating at their ends with upper and lower portions thereof, gas burners arranged below the coils and conforming substantially to the ends thereof, and a burner extending longitudinally of the gas heated compartment and arranged to direct a flame toward the lower portion of the water compartment.

7. In a combined coal and gas water heater, the combination with a water compartment forming one wall of a fire-box, of a gas heated chamber located adjacent to the fire-box, a series of comparatively short and wide water conducting coils arranged vertically in the gas heated chamber and communicating at their ends with upper and lower portions of the water compartment, and gas heating means located beneath the coils.

HUGO A. BECKER.
ALFRED D. DUKELOW.
